UNITED STATES PATENT OFFICE

104,370

DESIGN FOR A MAGNETO-ELECTRIC GENERATOR

Le Roy S. Dunham, East Orange, and Arthur F. Robertson, Belleville, N. J., assignors to Edison-Splitdorf Corporation, West Orange, N. J., a corporation of New Jersey

Application March 5, 1937, Serial No. 68,008

Term of patent 7 years

To all whom it may concern:

Be it known that we, Le Roy S. Dunham and Arthur F. Robertson, citizens of the United States, residing at East Orange and Belleville, in the county of Essex, State of New Jersey, respectively, have invented a new, original, and ornamental Design for a Magneto-Electric Generator, of which the following is a specification, reference being had to the accompanying drawing, forming a part thereof.

Figure 1 is a side elevational view of a magneto-electric generator showing our new design.

Figure 2 is a view of Figure 1, looking from left to right.

Figure 3 is an end view of Figure 1, looking from right to left.

Figure 4 is a top view of Figure 1.

Figure 5 is a bottom view of Figure 1.

The magnetoelectric generator of the present design is adapted to be used in connection with a four-cylinder engine.

We claim:

The ornamental design for a magneto-electric generator as shown and described.

LE ROY S. DUNHAM.
ARTHUR F. ROBERTSON.
